CLAIM

The ornamental design for an inside corner piece for rain gutters, as shown and described.

DESCRIPTION

FIG. 1 is a pictorial view from above and the front of an inside corner piece for rain gutters according to a first embodiment of the invention

FIG. 2 is a pictorial view from above and the rear of the inside corner piece for rain gutters shown in FIG. 1.

FIG. 3 is a plan view of the inside corner piece for rain gutters shown in FIGS. 1 and 2.

FIG. 4 is an end view from the right side of the inside corner piece for rain gutters shown in FIGS. 1-3.

FIG. 5 is an end view from the left side of the inside corner piece for rain gutters shown in FIG. 1-4.

FIG. 6 is a rear view of the left side of the inside corner piece for rain gutters shown in FIGS. 1-5.

FIG. 7 is a rear view from the right side of the inside corner piece for rain gutters shown in FIGS. 1-6.

FIG. 8 is a bottom view of the inside corner piece for rain gutters shown in FIGS. 1-7.

FIG. 9 is a pictorial view from the front of a second embodiment of an inside corner piece for rain gutters shown in FIGS. 1-8.

FIG. 10 is a pictorial view from the rear of the second embodiment of the inside corner piece for rain gutters shown in FIG. 9.

FIG. 11 is a pictorial view from the front of a third embodiment of an inside corner piece for rain gutters according to the invention.

FIG. 12 is a pictorial view from the rear of the inside corner piece for rain gutters shown in FIG. 11.

FIG. 13 is a pictorial view from the front of a fourth embodiment of an inside corner piece for rain gutters according to the invention; and,

FIG. 14 is a pictorial view from the rear of the inside corner piece for rain gutters shown in FIG. 13.
